UNITED STATES PATENT OFFICE.

CONRAD J. JOHNSON, OF CORRECTIONVILLE, IOWA.

WIRE-PLIERS ATTACHMENT.

1,147,510.

Specification of Letters Patent. Patented July 20, 1915.

Application filed October 30, 1914. Serial No. 869,382.

To all whom it may concern:

Be it known that I, CONRAD J. JOHNSON, a citizen of the United States, and a resident of Correctionville, in the county of Woodbury and State of Iowa, have invented a new and Improved Wire-Pliers Attachment, of which the following is a full, clear, and exact description.

5 My invention relates to an attachment for wire pliers, which attachment is a wire cleaner preferably detachable from the pliers.

10 The object of the invention is to provide a simple, convenient and inexpensive wire cleaner which can be easily and quickly attached to any wire pliers and whereby wires to be spliced can be easily and quickly cleaned by the attachment carried by the pliers without the aid of any auxiliary tool, 15 as is customary.

15 With the above and other objects in view, the nature of which will more fully appear as the description proceeds, the invention consists in the novel construction, combination and arrangement of parts as herein 20 fully described, illustrated and claimed.

25 In the accompanying drawings, forming part of the application, similar characters of reference indicate corresponding parts in 30 all the views, and Figure 1 is a perspective view of my invention illustrating the same as attached to pliers; Fig. 2 is a side elevation of the attachment without the abrasive block; Fig. 3 is an end elevation of the attachment; and Fig. 4 is a fragmentary perspective view of a modified attachment without the block.

35 Referring to the drawings, 4 represents a pair of wire pliers to the handle of which my attachment is secured. The attachment, 40 preferably, consists of a cross-shaped blank 5, the two opposite arms of which are bent in the same direction at right angles to the central portion of the blank so as to form a yoke. Each of the arms 6 is provided with 45 an elongated slot 7, through which slots a screw 8 is passed, whereby the attachment is clamped to the handle of the pliers. Of course any other suitable means can be used 50 for attaching the blank. The other arms 9 of the blank are both bent in the opposite direction to the arms 6. The said arms are, preferably, arcuated so that the convex sides thereof are facing. The two arms 7 are 55 resilient enough so as to clamp an abrasive

block 10, the sides of which block are concave. The distance between the sides of the abrasive block is greater than the distance between the convex sides of the arms 9; consequently the arms 9 yield slightly when the 60 block is forced therebetween, thus clamping the abrasive block to the member 5.

In the structure shown in the modified figure, the arms 6' are made resilient, with their end edges bent inwardly substantially 65 at right angles to the main portion of the arms 6' and which are adapted to engage the under side of the handle of the pliers when said attachment is forced on said handle from the end thereof, the resiliency of the 70 arm 6' clamping the attachment thereto. The yielding arcuated arms 9' at each side thereof are provided with inwardly directed projections 11 intended to engage the end surface of the abrasive block 10 when the 75 same is fitted between the arms 9'. These projections 11 will prevent a lateral movement of the block 10 in the attachment 5. In using the attachment on the pliers, the same is moved laterally when cleaning a wire by 80 means of the attachment, as can be easily understood. It will be noted that my attachment consists of an abrasive block and a retainer for same adapted to be secured to 85 pliers.

85 From the foregoing description, taken in connection with the accompanying drawings, the advantage of the construction and operation of the device shown will be readily understood by those skilled in the art to 90 which the invention pertains, and while I have described the principle of operation, together with the device which I now consider to be the best embodiment thereof, I desire to have it understood that the device shown 95 is merely illustrative and that such changes may be made as are within the scope of the appended claims.

Having thus described my invention, I claim as new and desire to secure by Letters 100 Patent:

1. In an attachment of the class described, a blank having a pair of resilient, arcuated arms the convex sides of which are facing, and an abrasive block having concave sides 105 fitting tightly between said arcuated arms said arcuated arms having means at the sides thereof adapted to engage said abrasive block, said blank having a pair of facing arms directed in an opposite direction from 110

the arcuated arms, and means associated with said last mentioned arms whereby the attachment can be secured.

2. As an article of manufacture, an attachment for pliers consisting of a cross-shaped blank the two opposite arms of which are bent at right angles to the blank, the other two arms being bent in the opposite direction and arcuated so that the convex sides 10 are facing, all of said arms being resilient, the first mentioned arms being provided with means whereby the attachment can be detachably secured to the pliers, and an abrasive block having concave sides made to 15 fit tightly between the arcuated arms, said arcuated arms having projections at the sides thereof for preventing the lateral displacement of the abrasive block between the arcuated sides.

3. In an attachment of the class described, 20 a blank having a pair of resilient arcuated arms facing each other, and an abrasive block having concave sides adapted to fit snugly between said arcuated arms, said blank having another pair of facing arms 25 extending in the opposite direction, said second pair of arms lying in a plane at right angles to the plane of the arcuated arms, said last mentioned pair of arms having means whereby said attachment can be secured. 30

In testimony whereof I have signed my name to this specification in the presence of two subscribing witnesses.

CONRAD J. JOHNSON.
